AIR CONDITIONING SYSTEM

Filed Dec. 11, 1937

UNITED STATES PATENT OFFICE

2,170,232

AIR CONDITIONING SYSTEM

George D. Bower, Columbia Heights, Minn., assignor to Minneapolis-Honeywell Regulator Company, Minneapolis, Minn., a corporation of Delaware

Application December 11, 1937, Serial No. 179,317

8 Claims. (Cl. 236—11)

This invention relates to an air conditioning system and more particularly to a warm air heating system in which a circulating fan circulates air through the heating chamber of a furnace and through a space to be heated, and in which a draft and a check damper are operated to control the rate of combustion in the furnace. The invention is more particularly concerned with the controls for the fan and dampers.

5 In such a system, it is often desirable to circulate unheated air through the heating chamber and the space during the summer-time so that the circulation of unheated air will have a cooling effect on the occupants of the space, and 10 to provide means responsive to the temperature 15 of the space for controlling the operation of the air circulating means. It often happens that during the summer-time when the furnace is shut down, that an unseasonable cold spell occurs, in 20 which case it may be desirable to burn some trash in the furnace to take the chill off the house, and in such case the dampers should be in draft producing position in order that the trash may burn 25 readily, but should the temperature in the heating chamber be raised to an excessive value, the dampers should be moved to draft retarding position to check the combustion of the trash.

When the system is being used for a heating system, the dampers should be placed in draft 30 producing position when it is desired to stoke the furnace in order to prevent smoke or gas from blowing out of the firing door of the furnace, as would be liable to happen particularly should the check damper be open.

35 In order to conveniently control the operation of the dampers and fan in winter and summer, and to control the dampers during the stoking period I have devised a system in which the control is changed merely by the manipulation of 40 a three-position switch. When the switch is in one position, the fan is under the control of a room thermostat and a switch responsive to the temperatures of the heating chamber, so that the fan is operated only upon a call for heat in 45 said room providing the temperature of the heating chamber is sufficiently high. In this position of the switch, the dampers are moved to draft producing position only when there is a call for heat in said room. When the switch is moved 50 to a second position, the operation of the fan is unaffected, but the dampers are moved to draft producing position regardless of the temperature of the room. The dampers are under the control of a switch which opens should the temperature 55 of the heating chamber attain an excessive pre-

determined value whereupon the dampers are moved to draft retarding position. When the three-position switch is moved to a third position, the dampers are controlled in the same way as when the switch is in the second position, being normally in draft producing position, and the control of the fan by the room thermostat is changed so that the fan is operated only when the temperature of the room is above a certain value. This third position is the summer position, and since the dampers are normally in draft producing position, further manipulation thereof is unnecessary should it be desired to burn trash in the furnace during the summer operation of the system.

5 It is therefore an object of my invention to provide an improved operating system for a warm air coal fired furnace in which air circulating means are provided to circulate air over the heating chamber and through a space to be heated.

10 More specifically, it is an object of my invention to provide, in such a system, a single three-position switch by means of which the system operates as a heating system in one position of the switch to circulate air through the heating 15 chamber of the furnace and through a space to be heated only when heat is required in said space, and to move draft controlling dampers to draft producing position at such time; by means of 20 which the dampers are moved to draft producing position for purposes of stoking the furnace, regardless of the temperature of the space in a second position of the switch; and by means of 25 which the fan is caused to operate when the temperature of the space is above a predetermined 30 value in the third, or summer position of the switch, and in which position of the switch the dampers are normally held in draft producing 35 position.

40 It is a further object of my invention to provide control means for draft dampers in such a system, whereby the dampers are moved to draft producing position only when heat is required in the space being heated during the normal winter operation of the system, and whereby the dampers are normally held in draft producing position 45 in the summer operation of the system, there being a switch responsive to the temperature of the heating chamber whereby the dampers are moved to draft retarding position whenever the temperature of the heating chamber rises above a predetermined value, in either the winter or summer 50 operation of the system.

55 Other objects will become apparent upon an examination of the specification, claims and draw-

ing, in which the single view illustrates the preferred form of my system.

Referring more particularly to the drawing a warm air furnace is indicated by a reference character 10. This furnace includes the usual warm air ducts 11, an outlet stack 12, a draft damper 13, a check damper 14, and a firing door 15. A blower 16 is provided for circulating air through the heating chamber of said furnace 10 and through a space or spaces being heated. For driving said blower 16 a motor 17 is provided, said motor having a pulley 18 connected by a belt 19 to a pulley 20 which is connected to the blower.

15 Mounted in the heating chamber of the furnace is a bimetallic element 21 of conventional design operatively connected by a rod 22 to mercury switches 23, 24, and 25 in a well known manner. Switch 23 includes a mercury element 26 and contacts 27 and 28 which are normally closed by the mercury element 26. Switch 24 includes a mercury element 30 and contacts 31 and 32, and switch 25 includes a mercury element 33 and contacts 34 and 35, these last two switches being 20 normally in open position as illustrated. Switch 25 is designed to tilt to closed position upon the attainment of one predetermined temperature in the heating chamber, switch 23 tilts to open position upon the attainment of a higher predetermined temperature in the heating chamber and switch 25 tilts to closed position upon the attainment of a still higher temperature in the heating chamber.

For operating the draft and check dampers 13 35 and 14 an arm 40 is provided, said arm being connected to the draft damper 13 by means of a cable or like member 41, the other end of said arm being connected to the check damper 14 by means of a cable 42 passing over a pulley 43. The arm 40 is mounted at its center on a shaft 44 and movement of arm 40 by shaft 44 in a clockwise direction will cause the opening of draft damper 13 and the closing of check damper 14 as will be apparent.

40 For rotating shaft 44, a motor generally indicated by the reference character 50 is provided, this motor including an armature 51 and field windings 52 and 53. Field winding 52 acts as a lifting coil for the armature 51 and winding 53 45 acts as a holding coil. Thus, if winding 52 is initially energized, shaft 44 will be rotated to move arm 40 in a clockwise direction, after which this coil is deenergized as will be explained hereafter but the arm 40 will remain in its new position as long as field winding 53 remains energized. Rigidly mounted on the shaft 44 is an arm 54 to which is connected a spring 55 for biasing said arm in a counter-clockwise direction when the field winding 53 is deenergized. A stop 56 50 limits the movement imparted to arm 54 by the spring 55. Shaft 44 is connected to the armature 51 through a reduction gearing 57.

In the circuit of field winding 52 is a switch 60 which includes a switch arm 61 and a fixed contact 62. Mounted on shaft 44 for rotation therewith is a cam 63 having a recessed portion 64. Switch arm 61 has a projection 65 for cooperating with said recess 64 when the cam 63 has rotated through approximately 90°. As will be 65 apparent cam 63 bears against the portion 65 of the switch arm and normally holds said arm in engagement with the fixed contact 62 but upon sufficient rotation of shaft 44 the recess 64 will 70 lie directly above the portion 65 of the switch 75

arm and permit said arm to move upwardly and away from fixed contact 62.

Slidably mounted in walls 70 and 71 is a switch actuator 72 normally biased toward the right by means of a spring 73 acting upon the shoulder 74 of said actuator. Member 72 has a reduced portion 75 for cooperation with an aperture 76 in the arm 54. At the opposite end of member 72 is an energized portion 77 and a handle member 78, enlarged portion 77 being designed to move 10 a switch arm 79 into engagement with a second switch arm 80 when member 72 is moved to the left against the action of spring 73. When the motor 50 is deenergized, damper operating arm 40 may be moved in a clockwise direction by 15 hand and if it is moved to a position wherein the aperture 76 is opposite the reduced portion 75 of member 72, this member may be forced to the left to a position wherein the reduced portion 75 of member 72 passes through the aperture 76 in 20 the arm 54. With the parts in this position, the spring 55 will bias arm 54 in a counter-clockwise direction and the frictional engagement between the reduced portion 75 of member 72 and the wall of aperture 76 will hold member 72 in 25 the switch closing position against the action of spring 73. A slight movement of arm 54 in a clockwise direction will relieve the frictional engagement between reduced portion 75 of member 72 and the wall of aperture 76 whereupon 30 the switch actuating member 72 will be moved to the right by means of the spring 73 and switch arm 79 will move away from switch arm 80. The function of switch arms 79 and 80 will be 35 explained later.

40 A three-position switch generally indicated by the reference character 84 is provided and includes an actuator 85, switch arms 86 and 87 and contacts 88 and 89 cooperating with said switch arms. Switch arm 86 is normally biased toward the right and arm 87 is normally biased toward the left. If the actuator 85 is rotated in a clockwise direction through 90°, the switch arm 87 will be permitted to move into engagement with the contact 89. Movement of actuator 85 in the 45 same direction through another 90° will cause the arm 86 to move into engagement with the fixed contact 88, arm 87 remaining in engagement with contact 89. This switch is for the purpose of providing for summer and winter operation of 50 the system and for placing the draft dampers in a firing position during the winter time as will be hereinafter explained.

55 Mounted in the space to be heated is a thermostat 90, said thermostat including a bimetallic element 91 and arms 92 and 93 arranged to be moved thereby. Arm 92 is relatively flexible and is arranged to engage a fixed contact 94 upon a predetermined drop in the room temperature. Arm 93 does not engage its fixed contact 95 until 60 a further slight drop in room temperature, movement of this arm into engagement with contact 95 being permitted by reason of the flexibility of arm 92.

65 For controlling the operation of the damper motor and blower motor a relay generally indicated by the reference character 97 is provided. This relay includes a coil 98, an armature 99, and switch arms 100, 101, and 102 operated thereby. Cooperating with arm 100 is a fixed contact 103, 70 70 cooperating with switch arm 101 are contacts 104 and 105, and cooperating with the switch arm 102 is a fixed contact 106. These switch arms are normally in the positions illustrated when the coil 98 is not energized, in which position switch

arm 101 is in engagement with contact 105 and switch arms 100 and 102 are out of engagement with their respective contacts. Energization of the coil 98 causes switch arms 100, 101, and 102 to move into engagement with contacts 103, 104, and 106, respectively.

For energizing the damper motor and blower motor, lines 110 and 111 are provided, these lines being connected to a suitable source of power 10 (not shown). A step-down transformer 112 is provided for furnishing power to the relay 97, this transformer including a high tension primary 113 connected by means of conductors 114 and 115 to the lines 110 and 111, and a low tension secondary 116.

With the parts in the position illustrated, the room thermostat is satisfied, that is, it is not calling for more heat in the space being heated. Damper motor 50 is deenergized and spring 55 20 biases the arm 54 against the stop 56 in which position the damper arm 40 is positioned as illustrated, the check damper 14 is open and the draft damper 13 is closed so that the draft through the furnace is at a minimum. Also the blower motor 17 is deenergized so that no air is being circulated through the system by the blower 16.

Assume the temperature in the space drops to a certain predetermined value. The bimetallic element 91 will cause arm 92 to move into engagement with contact 94, but no circuit through the relay 98 is created at this time. If the temperature drops to a further predetermined value arm 93 will be moved into engagement with contact 95 whereupon the coil 98 of relay 97 will be energized through the following circuit: from the low tension secondary 116 of transformer 112 through conductor 120, contact 94, arms 92 and 93 of the thermostat 90, contact 95, conductor 121, coil 98 and conductor 122 to the other side 40 of secondary 116. Energization of coil 98 will cause switch arms 100, 101, and 102 to move into engagement with contacts 103, 104, and 106 as explained heretofore. Movement of arm 100 into engagement with contact 103 energizes a holding circuit for the relay coil 98, which circuit is independent of the arm 93, this circuit being as follows: from the low tension secondary 116 through conductor 120, contact 94, thermostat arm 92, bimetallic element 91, conductor 123, contact 103, switch arm 100, conductor 124 through the relay coil 98 and conductor 122 to the other side of secondary 116. It will therefore be seen that relay coil 98 will be energized as long as blade 92 remains in contact 94 so that the circuit through coil 98 will not be broken at the same temperature as that at which it is made but rather at a slightly higher temperature.

Movement of switch arm 102 into engagement with contact 106 energizes the damper motor 50 60 through the following circuit: from the line 110 through conductors 130, 131, contacts 28 and 27 which are closed by the mercury element 26, conductors 132, 133, contact 106, switch arm 102, conductors 134, 135, 136, contact 62, switch arm 61, conductor 137 through the lifting coil 52 of the damper motor and conductor 138 to the line 111. Energization of coil 52 causes rotation of the armature 51 to move the shaft 44 in a clockwise direction. At the same time a circuit is established through a holding coil 53 which circuit is as follows: from the line 110 through conductors 130, 131, contacts 28 and 27 of switch 23, conductors 132, 133, contact 106, switch arm 102, conductors 134, 135, 139, the holding coil 53 and conductor 140 to the line 111. It will be noticed

that the circuit through the holding coil 53 is independent of switch 60 whereas the circuit through the lifting coil 52 passes through this switch. After the shaft 44 has rotated through approximately 90°, the cam 63 moves to a position wherein the recess 64 lies directly over the projecting portion 65 of switch arm 61, whereupon switch arm 61 is permitted to move upwardly and out of engagement with contact 62 thus deenergizing the lifting coil 52. Holding coil 53 10 is designed to maintain shaft 44 in its new position against the action of spring 55 which tends to move it back to its original position.

In this new position of shaft 44 the arm 40 has moved clockwise through 90° causing the 15 draft damper 13 to open and the check damper 14 to close. The temperature of the heating chamber now commences to rise by reason of the increased combustion of fuel in the furnace 10 occasioned by the increased draft and after 20 the temperature in the heating chamber rises to a certain predetermined value, bimetallic element 21 causes mercury switch 24 to tilt to a position wherein contacts 31 and 32 are closed by the mercury element 30. A circuit through 25 the blower motor 17 is now established, this circuit being as follows: from the line 110, conductor 130, 145, contacts 32, 31, conductor 146, contact 104, switch arm 101, conductors 147, 148, terminal 149 of the blower motor through 30 the motor to terminal 150 and conductor 151 to the line 111. Operation of the blower motor causes a circulation of air through the heating chamber of the furnace and the space within which the thermostat 90 is located.

After the temperature of said space reaches a certain high value wherein the arms 92 and 93 are moved out of engagement with their respective contacts, the circuit through the relay coil 98 is broken and the switches move back to 40 their original positions. This causes deenergization of the blower and damper motors since the circuits for these motors pass through the switch arms 101, 102 and contacts 104 and 106, respectively. Spring 55 causes arm 54 and shaft 44 45 to move back to its original position whereupon arm 40 is also moved back to its original position in which position the draft damper 13 is closed and the check damper 14 is open.

Assume now that before the room thermostat 50 90 is satisfied that the temperature of the heating chamber rises beyond a certain predetermined value. Switch 23 will be tilted to its open position whereupon the damper motor is deenergized but the blower motor 17 continues to 55 operate until the room thermostat 90 is satisfied. If the temperature of the heating chamber rises to a still higher value after the room thermostat is satisfied and the damper motor is deenergized, the switch 25 will be tilted to a 60 position wherein the mercury element 33 closes the contacts 34 and 35. The blower motor 17 will again be energized to cause a dissipation of this excessive heat in the heating chamber, the circuit through the motor now being as follows: from the line 110 through conductors 130, 160, contacts 35 and 34, conductors 161 and 148, terminals 149 and 150, and conductor 151 to the line 111. This circuit through the blower motor is controlled only by the switch 25 so that regardless of the temperature in the space being heated the blower motor 17 will operate whenever the temperature of the heating chamber for any reason reaches an excessively high value.

Should it be desired to throw fuel in the fur- 75

nace at a time when the dampers are in their draft checking positions as illustrated it will be desirable to move them to draft producing positions to prevent smoke and gases from being blown out of the firing door 15 and into the furnace room. Since the damper motor 50 is de-energized, it being assumed now that the room thermostat is satisfied when it is desired to throw on the fuel, switch actuator 85 may be moved 10 clockwise 90° in which position the switch arm 87 engages contact 89 and will cause operation of the damper motor regardless of the temperature in the space being controlled, the circuit through the lifting coil 52 of the motor being as follows: from line 110 through conductors 130, 131, contacts 28 and 27 of switch 23, conductors 132, 165, contact 89, switch arm 87, conductors 166, 135, 136, contact 62, switch arm 61, conductor 137, lifting coil 52 and conductor 138 to the line 111. The circuit is established 15 through the holding coil 53 as follows: from the line 110 through conductors 130, 131, contacts 28, 27, conductors 132, 165, contact 89, switch arm 87, conductors 166, 135, 139, the holding coil 53 and conductor 140 to the line 111. It will be 20 apparent now that the dampers will be moved to their draft producing positions whereupon fuel may be thrown on the fire bed. After the furnace has been fired the switch 85 should be moved back to its original position placing the damper 25 motor under the control of the room thermostat. Should the operator of the furnace neglect to do this however, the temperature of the heating chamber will gradually rise until the switch 30 23 is tilted to open position, thus breaking the circuits through the damper motor. Since the blower motor is not placed in operation, very little heat will be delivered to the space being heated.

40 In case of power failure the dampers may be manually moved to open position should the temperature of the space being heated fall to an undesirable low value. This is done by manually moving arm 40 in a clockwise direction until aperture 76 is opposite the portion 75 of 45 member 72, and then moving member 72 toward the left until member 75 passes through the aperture 76. Spring 55 holds the member 75 in its new position by reason of the frictional engagement of the wall of the aperture and the member 75. This causes the dampers to remain 50 in their draft producing position as long as the frictional engagement produced by the biasing effect of spring 55 exists. Switch elements 55 79 and 80 are now closed by reason of the movement of member 72 to the left. Members 54 and 63 are so related that when reduced portion 75 of member 72 extends through aperture 76 the recess 64 has not quite reached a position which 60 permits the arm 61 to move upwardly out of engagement with contact 62.

Upon a restoration of power to the lines 110 and 111 the damper motor will revert back to automatic operation. A circuit through the lifting coil 52 will be established regardless of the temperature of the space being heated and of the heating chamber, this circuit being as follows: from line 110 through conductors 170, 171, switch members 80 and 79, conductors 172, 139, 65 136, contact 62, switch arm 61, conductor 137 through the lifting coil 52 and through conductor 138 to the line 111. Damper motor 51 now causes shaft 44 to commence rotating in a clockwise direction and as soon as this happens the frictional engagement between members 75 and

aperture 76 is relieved and spring 55 causes member 72 to move to the right thus breaking the circuit through switches 79 and 80. If the room thermostat 90 is not satisfied at this time and the temperature of the heating chamber is below 5 the value required to open switch 23, it will be apparent that the damper motor will remain energized, holding the dampers in their draft producing position. If, however, the room thermostat is satisfied or the temperature of the heating chamber is high enough to cause switch 23 10 to move to open position the damper motor will be deenergized as soon as switch elements 79 and 80 are moved apart and biasing spring 55 will cause a return of the dampers to their draft 15 retarding positions.

In the summer-time when there is no fire in the furnace it may be desirable in hot weather to operate the blower 16 to circulate unheated air through the heating chamber of the furnace and 20 the space under control of the thermostat 90 whenever the temperature of the space is above a certain predetermined value. In order to do this switch member 85 is rotated through 180° 25 from the position shown, in which position switch blades 86 and 87 are in engagement with contacts 88 and 89, respectively.

When relay coil 98 is deenergized and switch arm 101 is in engagement with contact 105 a circuit through the blower motor is established 30 as follows: from line 110 through conductors 170, 175, contact 88, switch arm 86, conductor 176, contact 105, switch blade 101, conductors 147, 148, terminal 149 of motor 17, through the motor to terminal 150 and conductor 151 to the 35 line 111. The blower motor 17 will continue to operate to cause a circulation of air through the space under the control of thermostat 90 until such time as the temperature of said space drops to a certain predetermined value. At this 40 time the blades 92 and 93 of said thermostat engage contacts 94 and 95, respectively, causing relay coil 98 to be energized, as previously explained, whereupon the switch arm 101 is moved out of engagement with contact 105 and the 45 circuit through the blower motor is interrupted. It is thus seen that during the summer-time the blower motor operates only when the room temperature reaches a certain high value, assuming 50 this switch 85 to be in its summer position.

In the summer position of switch 85 the damper motor 50 is energized through the circuit previously described when the switch 85 was in its firing position since switch blade 87 is engaged 55 with contact 89 in both the firing and summer positions of the switch actuator 85. Thus, if it is desired to burn some trash in the furnace to raise the temperature of the space during an unseasonable cold spell during the summer-time for example, there will be sufficient draft through the furnace to cause combustion of said trash. If now the temperature of the furnace begins to rise, as it of course will, and reaches a high enough value, it will be desirable to cause dampers 13 and 14 to move to draft retarding position. Upon the attainment of this high temperature the switch 23 will be tilted to a position in which contacts 27 and 28 are open, and since this switch is in the circuit of the damper motor, the 70 damper motor will be deenergized and the damper arm 40 moved back to the position illustrated by reason of the biasing effect of spring 55. The room thermostat 90, if the temperature of the space has fallen low enough, will cause a cir-

cuit through the relay coil 98 to be established as previously explained and cause the switch arm 101 to move into engagement with contact 104. When the temperature of the furnace reaches a certain high value, which as explained heretofore, is somewhat lower than the required value to cause switch 23 to open, the switch 24 will be closed and the blower motor 17 will be energized through the circuit described originally in the description of the winter operation of the system. The heat generated in the furnace by burning of the trash will now be circulated through the space under the control of the thermostat 90 thus raising the temperature to a desirable value.

It will thus be seen that with my system, when switch 84 is in the winter position, or the position illustrated, the energization of the blower and damper motors are under the control of the room thermostat and the blower motor is also under the control of the switch 24 responsive to the temperature of the heating chamber of the furnace so that it will not operate until the temperature reaches a certain high value. The damper motor is also under the control of the switch 23 which causes it to be deenergized upon the attainment of a still further high value in the heating chamber and a third switch 25 is provided for causing operation of the blower motor regardless of the space temperature should the temperature of the heating chamber for any reason reach a dangerously high value, whereby the heat may be dissipated, upon movement of switch 85 to its second or firing position the damper motor is operated to place the dampers in draft producing position to facilitate the firing of the furnace, the damper motor still being under the control of the switch responsive to temperatures of the heating chamber whereby the damper motor is deenergized should the attendant fail to move the switch 84 back to its normal winter position after he has finished firing the furnace. With the switch 84 in its third or summer position, the dampers are normally held in draft producing position, the damper motor being normally energized and the blower motor is under the control of the room thermostat but is operated only when the room temperature reaches a certain high value unless the temperature of the heating chamber of the furnace is for some reason raised to a certain value during the summer-time in which case the damper motor is automatically deenergized.

While I have illustrated and described the preferred embodiment of my invention it is capable of many modifications as will be apparent to those skilled in the art and I wish it to be understood that my invention is limited only by the scope of the appended claims.

60 I claim as my invention:

1. In a heating system, a warm air furnace, air circulating means for circulating air through the heating chamber of said furnace and through a space to be heated, a damper for controlling the draft through the furnace, a three-position switch, means for causing operation of said air circulating means when the temperature of the space is below a predetermined value and the temperature of the heating chamber is above a predetermined value and causing the damper to be moved to draft producing position when the temperature of the space is below a predetermined value when said switch is in one position, means causing the damper to be moved to draft producing position regardless of the temperature

of the space when the switch is moved to a second position and means causing operation of said air circulating means when the temperature in the space is above a predetermined value in response to the placing of the switch in a third position.

2. In a heating system, a warm air furnace, air circulating means for circulating air through the heating chamber of said furnace and through a space to be heated, a damper for controlling the draft through the furnace, a three-position switch, means for causing operation of said air circulating means when the temperature of the heating chamber is above a predetermined value and the temperature of the space is below a predetermined value and causing the damper to be moved to draft producing position when the temperatures of the heating chamber and space are below predetermined values in response to the placing of the switch in one position, means causing the damper to be moved to draft producing position when the temperature of the heating chamber is below a predetermined value regardless of the temperature of the space, in response to the placing of said switch in a second position, and means causing operation of said air circulating means when the temperature of the space is above a predetermined value in response to the placing of the switch in a third position.

3. In a warm air heating system, a warm air furnace having a heating chamber, air circulating means for circulating air through said chamber and through a space to be heated, a thermostat responsive to temperatures in the space to be heated, a switching means having a winter position, a firing position and a summer position, means responsive to movement of said switching means to winter position for causing operation of the air circulating means when the temperature of the heating chamber is above a predetermined value and the temperature of the space is below a predetermined value and causing movement of the damper to draft producing position when the temperature of the space is below a predetermined value, means responsive to the movement of the switching means to firing position to change the control of the damper only to cause the same to be moved to draft producing position regardless of the temperature of the space, and means responsive to the movement of the switching means to summer position to cause operation of the fan whenever the temperature of the space is above a predetermined value and to cause movement of the dampers to draft producing position.

4. In a warm air heating system, a warm air furnace having a heating chamber, air circulating means for circulating air through said chamber and through a space to be heated, a thermostat responsive to temperatures in the space to be heated, a switching means having a winter position, a firing position and a summer position, means responsive to movement of said switching means to the winter position for causing operation of said air circulating means when the temperature of the heating chamber is above a predetermined value and the temperature of the space is below a predetermined value and causing movement of the damper to draft producing position when the temperatures of the heating chamber and space are below predetermined values, means responsive to the movement of the switching means to firing position to change the control of the damper only to cause the same to be

5 moved to draft producing position providing the temperature of the heating chamber is below a certain predetermined value regardless of the temperature of the space, and means responsive to the movement of the switching means to summer position to cause operation of the fan whenever the temperature of the space is above a predetermined value and to cause movement of the dampers to draft producing position whenever 10 the temperature of the heating chamber is below a predetermined value.

5. In a heating system, a warm air furnace, means for circulating air through the heating chamber of said furnace and through a space to be heated, a damper for controlling the temperature of said heating chamber, a motor for operating said damper, space temperature responsive means, a three-position switch, a first temperature responsive switch, a second temperature responsive switch, said first switch closing upon the attainment of a predetermined temperature in the heating chamber and the second switch opening upon the attainment of a higher predetermined temperature in the heating chamber, means placing the air circulating means under the control of the space temperature responsive means and the first temperature responsive switch and means placing the damper motor under the control of said space temperature responsive means and said second temperature responsive switch with the three-position switch in one position, means placing the damper motor under control of the second temperature responsive switch alone whereas the space temperature responsive means and the first temperature switch retain control of the air circulating means in the second position of the three-position switch, and means placing the air circulating means under control of the space temperature responsive means alone while the second temperature responsive switch retains control of the damper motor in the third position of said switch.

6. In a heating system, a warm air furnace, means for circulating air through the heating chamber of said furnace and through a space to be heated, a damper for controlling the temperature of said heating chamber, a motor for operating said damper, space temperature responsive means, a three-position switch, a first temperature responsive switch, a second temperature responsive switch, a third temperature responsive switch, said first temperature responsive switch closing upon the attainment of a predetermined temperature in the heating chamber, said second temperature responsive switch being normally closed and opening in response to the attainment of a higher temperature in the heating chamber, said third temperature responsive switch being normally open and closing in response to the attainment of a still higher temperature in said heating chamber, means whereby the air circulating means is under the control of the space temperature responsive means and the first temperature responsive switch and whereby the damper motor is under the control of the space temperature responsive means and said second temperature responsive switch with the three-

position switch in one position, means whereby the damper is under control of the second temperature responsive switch alone whereas the space temperature means and the first temperature responsive switch retain control of the air circulating means with the three-position switch in a second position, means whereby the space temperature responsive means alone may control the air circulating means while the second temperature responsive switch retains control of the damper motor in the third position of said switch, and means independent of said three-position switch for causing operation of said air circulating means in response to the closing of said third temperature responsive switch.

7. In an air conditioning system, a warm air furnace, means for circulating air through the heating chamber of said furnace, a damper for controlling the draft through said furnace, a motor for operating said damper, a summer-winter switch, means causing said motor to operate to open said damper in response to the attainment of a low predetermined temperature in said space and causing said air circulating means to operate in response to the attainment of a low predetermined temperature in said space and the attainment of a high predetermined temperature in said heating chamber when said switch is in the winter position, means causing said damper motor to open the damper in response to movement of said switch to summer position, means causing said air circulating means to operate in response to the attainment of a high predetermined temperature in said space when said switch is in summer position, and means, independent of said switch, for causing said damper motor to close said damper in response to the attainment of a high predetermined temperature in said heating chamber.

8. In a temperature controlling system, a warm air furnace including a heating chamber and means for circulating air through said heating chamber and through a space to be heated, controlling means rendering said circulating means selectively responsive either to the attainment of a low predetermined temperature in said space or to the attainment of a high predetermined temperature in said space, draft controlling means for controlling the draft through said furnace, means for causing operation of said draft controlling means to cause maximum draft through said furnace in response to the attainment of a low predetermined temperature in said space when said controlling means is operated to render said air circulating means responsive to the attainment of a low predetermined temperature in said space, and means causing operation of said draft controlling means to normally maintain maximum draft through said furnace when said controlling means is operated to render said air circulating means responsive to the attainment of a high predetermined temperature in said space, but causing operation of said draft controlling means to cause minimum draft through said furnace in response to the attainment of a high predetermined temperature in said heating chamber.

GEORGE D. BOWER.
